UNITED STATES PATENT OFFICE.

OSCAR ADOLF KRISTIAN PRINTZ, OF OFVERUM, SWEDEN.

PLOW.

Application filed September 10, 1925. Serial No. 55,593.

To all whom it may concern:

Be it known that I, OSCAR ADOLF KRISTIAN PRINTZ, a citizen of the Kingdom of Sweden, residing at Ofverum, Sweden, have 5 invented new and useful Improvements in Plows, of which the following is a specification.

This invention relates to plows and more particularly to mold-boards for plows.

10 It is proposed to manufacture mold-boards for plows of so called "soft-center" steel, that is, a steel comprising an intermediate layer of soft iron and two outer layers of a steel of high carbon content, capable of being hardened and welded to the said intermediate layer.

With reference to the accompanying drawing, Figure 1 is a section of part of such a mold-board of soft-center steel of 20 the hitherto used design together with a portion of the plow standard to which the mold-board is secured by means of screws. 1 indicates the standard, made in the well-known way of cast iron or steel that is not 25 hardened. 2 is the outer hardened layer of the mold-board, and 3 is the soft intermediate layer thereof. The arrow indicates the direction of movement of the plow. The point 4 of the section will thus lie on the 30 cutting edge of the mold-board when in operation. The limiting surfaces 5 and 6 of the cutting portion are in the operation of the plow subjected to a considerable wear, and as the layers of the mold-board are 35 comparatively thin the edge of the mold-board will soon become blunt and, after having been used for a rather short period of time, the section of the edge will be somewhat like that shown in Fig. 2 and, as 40 a result, the tractive power required for driving the plow must be substantially increased.

The present invention has for its object to overcome said inconvenience by stiffening

the edge of the mold-board so as to obtain 45 a greater depth as seen in the rearward direction while maintaining the alternate layers of hardened and non-hardened material of the mold-board also within the reinforced portions, at the same time increasing 50 the thickness of the various layers. According to this invention this result is obtained by forming the foremost cutting portion of the outer layer of the mold-board blank with a stiffening ridge on its rear 55 surface, said ridge being formed by bending and upsetting the foremost edge of the mold-board blank.

The invention is illustrated by way of example in Fig. 3 of the drawing. With 60 reference to Fig. 3, the numeral 7 indicates the plow standard, 8 are the two outer hardened layers, and 9 is the soft intermediate layer. The stiffening ridge at the 65 foremost edge of the mold-board is formed by bending the foremost portion of the mold-board blank through an angle of about 45° and upsetting said bent portion by a pressure directed towards the edge. Due to 70 this upsetting operation the advantage is obtained over the prior well known method that the operating surface, into which the 75 soft intermediate layer terminates, will be considerably larger and will essentially comprise material of the two hardened outer layers resistive to wear.

What I claim is:

A mold-board for plows comprising an intermediate layer of soft iron and two outer layers of hardened steel, in which the 80 foremost cutting edge of the outer layer of said mold-board is formed with a stiffening ridge on its rear side produced by bending and upsetting the foremost edge of the outer layer of said mold-board.

In testimony whereof I have signed my name.

OSCAR ADOLF KRISTIAN PRINTZ.
